UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

ENGINE AND COMPRESSOR CONTROL.

Application filed May 23, 1924. Serial No. 715,380.

This invention relates to apparatus for the automatic coordinated control of a fluid compressor or pump and its driving engine with relation to and in cooperation with a speed governor controlling the motive agent of the engine.

One object of the invention is to provide a simple, compact device readily applied to a governor of the described type to adapt the same to coordinated operation with the unloading mechanism of the compressor. Another object is to provide means on the device for convenient adjustment of the governor. Other objects will be apparent from the detailed description which follows.

Fig. 1 is a diagrammatical side elevational view largely broken away and partly in section disclosing an air compressor, its driving engine and the control apparatus for both; and

Fig. 2 is a vertical longitudinal sectional view on an enlarged scale of the motive agent control apparatus of the driving engine.

The embodiment of the invention chosen for the purpose of illustration is shown in Fig. 1 in its operative or functional relation with a fluid compressor or pump A of any suitable or desired type driven by a governor controlled prime mover which in the present instance is an internal combustion engine B, the driving connection between the compressor and the engine not being shown since the same forms no part of the present invention.

The compressor A is provided with any suitable type of fluid pressure operated unloading valve a, that illustrated being of the type disclosed in United States Patent No. 1,275,843 issued August 13, 1918, to W. H. Callan.

Control of the compressor in response to the receiver pressure developed by the latter is effected by a differential unloader valve C of the type disclosed in United States Patent No. 1,224,272 issued May 1, 1917, to W. H. Callan et al, or of any other suitable or desired type. The unloader valve C is connected to the air receiver (not shown) by a pipe c and controls the admission of pressure fluid to an outlet pipe c'.

which extends to unloading valve a by a branch c² for operating the latter. A branch c³ of the same line also extends to a control device for engine B, presently to be described, whereby the engine is throttled co-

ordinately with the unloading of the compressor.

Engine B, as illustrated, is equipped with a centrifugal governor D driven from any suitable portion of the engine, as its cam shaft (not shown), through a suitable connection which may include a flexible shaft d. The form of governor herein shown has a main housing d' forming a part of the intake connection from the motive agent supply or carburetor E and a fly ball housing d² bolted to the main housing d' and providing for the connection of the flexible shaft d thereto. Secured to the main housing d' on the opposite side to housing d², is a casing 3 containing the pneumatic throttle apparatus to which pipe c³ connects to adapt the same to be operated by motive fluid from unloader valve C.

Referring now to Fig. 2 for the disclosure of the specific details of the engine control apparatus and with special reference to the centrifugal governor, the flexible shaft d drives a hollow cylindrical shaft d³ supported in suitable bearings d⁴ and d⁵ in the housings d² and d' respectively. Centrifugal weights or fly balls d⁶ are supported and rotated by shaft d³ through links d⁷ connecting the weights to a fixed collar d⁸ on shaft d³ and by links d⁹ to a slideable collar d¹⁰ on the same shaft, the latter being urged into spaced relation with fixed collar d⁸ by a spring d¹¹ which encircles shaft d³. Moveable collar d¹⁰ carries a cross bar d¹² extending through slots in shaft d³ which on movement of collar d¹⁰ to the right under the action of centrifugal weights d⁶ bears against and moves a stem d¹³ slidably mounted within hollow shaft d³. This stem in turn contacts and moves a throttle control shaft d¹⁴ slidably mounted in main housing d' and carrying a block d¹⁵ threaded thereon having a pin and slot connection with the intake throttle valve F which in the present instance is of the grid type pivoted at f for oscillatory movement in cooperation with a fixed seat f' also of the grid type. A light spring f² constantly urges throttle valve F to open position, which position is determined by a fixed stop f³. A larger and heavier spring d¹⁶ encircles shaft d¹⁴ and bears against block 15 to likewise urge valve F to open position. Housing d' has a threaded opening d¹⁷ in axial alignment with

shaft d^{14} through which the latter, or an extension of the same, projects well beyond the housing d' and carries near its flattened outer end a collar d^{18} .

5 Casing 3 of the pneumatic throttle control device has a threaded boss 4 which cooperates with opening d^{17} and utilizes the latter as the means of attaching casing 3 to governor D, the extended end of shaft d^{14} being received within casing 3. One arm of a lever 5 pivoted at 6 within casing 3 is adapted to engage the collar d^{18} on shaft d^{14} to move the latter to the right to throttle the engine, the opposite end of lever 16 being engaged for this purpose by the stem 7' of a piston 7 which is subjected to the fluid pressure in pipe c^3 . Piston 7, as shown, is disposed in substantial parallelism with shaft d^{14} and moves in the opposite direction and may be provided with a spring 8 to resist the fluid pressure and to restore the piston to its normal inoperative position. An adjustable stop bolt 9 provided with a locking nut 10 limits the movement of lever 5 under the thrust of stem 7'.

To provide for adjustment of the idling position of throttle valve F while the engine is running, casing 3 has a threaded opening 9' in alignment with shaft d^{14} receiving a threaded plug 10' in which is rotatably mounted a shaft 11 carrying a slotted head 12 arranged to cooperate with the flattened end of shaft d^{14} , a manually operable knob 13 being provided for rotating shaft 11. Knob 13 has a serrated edge adapted to be frictionally engaged by a suitable latching spring 14 secured to casing 3 by screw 15. On rotating knob 13 shaft d^{14} is also rotated and the threaded connection of the latter with block d^{15} moves the latter longitudinally of shaft d^{14} to adjust the position of throttle valve F relative to its seat f' .

It is believed that the operation of both the centrifugal governor and the fluid pressure throttle control device will be evident from this disclosure; hence a detailed description thereof is omitted. From the above it will be apparent that the throttle control shaft d^{14} by reason of its manner of connection with both the centrifugal control and the fluid pressure control is adapted to be operated by either without interference from the other, that the fluid pressure control unit can be readily applied to or removed from a centrifugal governor of the type disclosed, that in adapting a centrifugal governor of the type shown to fluid pressure operation it is merely necessary to provide shaft d^{14} with a collared extension and flattened end or to insert a new shaft so provided and of greater length than the one used when the fluid pressure control device is not in place, and that the fluid pressure control device is simple, positive in operation and adapted to provide adjustment of the idling position of

the throttle valve while the engine is in operation without the use of tools or the removal of any parts.

While but one embodiment of the invention has been herein disclosed, it is to be understood that the invention is not limited thereto nor to the specific details thereof, but covers all changes, modifications and adaptations within the scope of the appended claims.

I claim:

1. The combination with an engine driven compressor of control means for the engine comprising a housing enclosing a centrifugal governor having a movable shaft operatively connected to the engine throttle, a casing secured to said housing and receiving an extension of said movable shaft, and fluid pressure operated means within said casing operable on unloading of the compressor for actuating said shaft to throttle the engine.

2. The combination with an engine driven compressor of control means for the engine comprising a housing enclosing a centrifugal governor having a movable shaft operatively connected to the engine throttle, a casing secured to said housing and receiving an axial extension of said movable shaft, a pneumatically operated piston in parallelism with said shaft, and an operative connection between said piston and said shaft whereby the unloading of the compressor causes throttling of its engine.

3. The combination with an engine driven compressor of control means for the engine comprising a housing enclosing a centrifugal governor having a movable shaft operatively connected to the engine throttle, a casing secured to said housing and receiving an extension of said movable shaft, fluid pressure operated means within said casing operable on unloading of the compressor for actuating said shaft to throttle the engine, and means on said casing for adjusting the connection of said shaft with the engine throttle.

4. The combination with an engine driven compressor of control means for the engine comprising a housing enclosing a centrifugal governor having a movable shaft operatively connected to the engine throttle, a casing secured to said housing and receiving an axial extension of said movable shaft, a pneumatically operated piston in parallelism with said shaft, an operative connection between said piston and said shaft whereby the unloading of the compressor causes throttling of its engine, and manual means on said casing operating through said extension for adjusting the connection of said shaft with the engine throttle.

5. The combination with an engine driven compressor of control means for the engine comprising a housing enclosing a centrifugal governor having a movable shaft operatively connected to the engine throttle, said housing

having a threaded opening in line with said shaft, a casing having a boss threaded into said opening, said shaft having an extension passing through said opening into said casing, and fluid pressure means operable on unloading of the compressor for actuating said shaft through said extension for throttling the engine.

6. The combination with an engine driven compressor of control means for the engine comprising a housing enclosing a centrifugal governor having a movable shaft operatively connected to the engine throttle, said housing having a threaded opening in line with said shaft, a casing having a boss threaded into said opening, said shaft having an axial extension passing through said opening into said casing, a collar on said shaft extension, a fluid pressure operated piston in parallelism with said extension, a lever pivoted intermediate its ends which engage respectively said collar and said piston whereby movement of said piston on unloading of the compressor produces throttling of the engine.

7. The combination with an engine driven compressor of control means for the engine comprising a housing enclosing a centrifugal governor having a movable shaft operatively connected to the engine throttle, said housing having a threaded opening in line with said shaft, a casing having a boss threaded into said opening, said shaft having an extension passing through said opening into said casing, manually operable means cooperating with the end of said extension for adjusting the operative connection of said shaft with the throttle, a fluid pressure operated piston adjacent said extension, and a lever having its extremities in engagement with said extension and with said piston respectively for transmitting movement of the piston responsive to unloading of the compressor to the throttle control shaft of the governor.

8. The combination with an engine driven compressor of control means for the engine comprising a housing enclosing a centrifugal governor having a movable shaft operatively connected to the engine throttle, said housing having a threaded opening in line with said shaft, a casing having a boss threaded into said opening, said shaft having an extension passing through said opening into said casing, a fluid pressure operated piston adjacent said extension and a lever having its extremities in engagement with said extension and with said piston respectively for transmitting movement of the piston responsive to unloading of the compressor to the throttle control shaft of the governor, and adjustable stop means for limiting the movement of said lever.

9. The combination with an engine driven compressor of control means for the engine

comprising a housing enclosing a centrifugal governor having a movable shaft operatively connected to the engine throttle, said housing having a threaded opening in line with said shaft, a casing having a boss threaded into said opening, said shaft having an extension passing through said opening into said casing, manually operable means cooperating with the end of said extension for adjusting the operative connection of said shaft with the throttle, a fluid pressure operated piston adjacent said extension and a lever having its extremities in engagement with said extension and with said piston respectively for transmitting movement of the piston responsive to unloading of the compressor to the throttle control shaft of the governor, and adjustable stop means for limiting the movement of said lever.

10. The combination with an engine driven compressor of control means for the engine comprising a housing having the fuel intake of the engine passing therethrough, a centrifugal governor having a shaft driven by the engine and connected to a throttle valve in said intake, an opening in line with said shaft, a casing secured in said opening, said shaft extending through said opening into said casing, means in said casing responsive to the unloading of the compressor for moving said shaft to throttle the engine, and means in said casing for varying the operative connection of said shaft and throttle while the engine is in operation.

11. A fluid pressure control device comprising a casing adapted for convenient attachment to the centrifugal governor housing of the driving engine of a compressor, said housing having an opening in line with the movable shaft of the governor, an extension for said shaft within said casing, and fluid pressure means responsive to unloading of the compressor for actuating said shaft to throttle the engine.

12. A fluid pressure control device comprising a casing adapted for convenient attachment to the centrifugal governor housing of the driving engine of a compressor, said housing having an opening in line with the movable shaft of the governor, an extension for said shaft within said casing, a fluid pressure operated piston adjacent said extension, and a lever in engagement with both said extension and said piston for transmitting movement of the latter in response to unloading of the compressor to said shaft to effect throttling of the engine.

13. A fluid pressure control device comprising a casing adapted for convenient attachment to the centrifugal governor housing of the driving engine of a compressor, said housing having an opening in line with the movable shaft of the governor, an extension for said shaft within said casing, a collar on said extension, a fluid pressure op-

erated piston in parallelism with said extension, and a lever having its extremities in operative relation with said collar and said piston for transmitting movement of the latter in response to unloading of the compressor to said shaft extension.

14. A fluid pressure control device comprising a casing adapted for convenient attachment to the centrifugal governor housing of the driving engine of a compressor, said housing having an opening in line with the movable shaft of the governor, an extension for said shaft within said casing, and manual means on said casing associated with said shaft extension for adjusting the throttle connection of said shaft while the engine is running.

15. A fluid pressure control device comprising a casing adapted for convenient attachment to a centrifugal governor housing of the driving engine of a compressor, said housing having an opening in line with the movable shaft of the governor, an extension for said shaft within said casing, a collar on said extension, a fluid pressure operated piston in parallelism with said extension, and a lever having its extremities in operative relation with said collar and said piston for transmitting movement of the latter in response to unloading of the compressor to said shaft extension, and means for adjustably limiting the throw of said lever.

16. A fluid pressure control device com-

prising a casing adapted for convenient attachment to the centrifugal governor housing of the driving engine of a compressor, said housing having an opening in line with the movable shaft of the governor, an extension for said shaft within said casing, a collar on said extension, a fluid pressure operated piston in parallelism with said extension, and a lever having its extremities in operative relation with said collar and said piston for transmitting movement of the latter in response to unloading of the compressor to said shaft extension, a stop for adjustably limiting the throw of said lever, and manual means on said casing associated with said shaft extension for adjusting the throttle connection of said shaft while the engine is running.

17. In a compressor controlling mechanism, a compressor, a driving engine therefor having a controlling valve normally maintained in one position, speed responsive means for controlling the position of said valve, pressure responsive means for controlling the position of said valve, and manual means for adjusting the normal position of said controlling valve without interfering with the operation of said speed responsive means and of said pressure responsive means.

Signed by me at Franklin, Pennsylvania, this 20th day of May 1924.

LEON F. HOFFMAN.
